UNITED STATES PATENT OFFICE.

CARL R. KLOK, OF CHICAGO, ILLINOIS, ASSIGNOR, BY MESNE ASSIGNMENTS, TO
UNITED TABLE-BED COMPANY, A CORPORATION OF VIRGINIA.

TABLE-BED.

1,243,426.

Specification of Letters Patent. Patented Oct. 16, 1917.

Application filed January 16, 1914. Serial No. 812,534.

To all whom it may concern:

Be it known that I, CARL R. KLOK, a citizen of the United States of America, and resident of Chicago, Cook county, Illinois, have invented a certain new and useful Improvement in Table-Beds, of which the following is a specification.

My invention relates to table beds of that kind in which the bed frame is concealed within the upper portion of the table, when the bed is not in use, and in which said frame is rotatively mounted on a carrier frame, the latter being in turn movably mounted on the table body.

The object of my invention, as herein disclosed, is to provide a novel construction and arrangement whereby the swiveled section of the bed frame, supported on the carrier frame, is right side up when the bed is folded within the table, and whereby the bed is easily and conveniently folded and unfolded, as will hereinafter more fully appear.

It is also an object to provide certain details and combinations tending to increase the general efficiency of a table bed of this particular character.

To these and other useful ends, my invention consists in matters set forth and claimed, as follows:

In the accompanying drawings—

Figure 1 is a longitudinal section of a table bed embodying the principles of my invention, on line 1—1 in Fig. 2, showing the bed folded within the table.

Fig. 2 is a section on line 2—2 in Fig. 1.

Fig. 3 is a view similar to Fig. 2, but showing the bed unfolded for use.

Fig. 4 is a view similar to Fig. 3, but showing the bed partially folded, showing how the bed is folded up outside of the table.

Fig. 5 is a view similar to Fig. 4, showing how the bed is pushed into the table, keeping the swiveled section of the bed frame right side up.

Fig. 6 is a horizontal detail section on line 6—6 in Fig. 2.

As thus illustrated, my invention comprises a table body A, having fixed legs a at the four corners thereof, fixed end walls a² and fixed side walls a³ and a fixed top a⁴, whereby a table is provided, having a hollow or box-like upper portion. The top section a⁴ is hinged at a⁵, and the movable side

wall a⁶ is hinged to the section a⁴, whereby the table may be opened at this side by folding back the said movable section and wall in the manner indicated in Fig. 3. The table thus formed is of the proper height for use as a library, or writing table, and has the requisite clearance below.

The folding bed B comprises a rectangular iron frame composed of sections b, b¹ and b², the said sections being pivotally connected together by means of links b³ and b⁴, the latter somewhat shorter than the former, whereby the section b² is between the sections b and b¹ when the bed frame is folded,

as shown in Figs. 2, 4 and 5. The section b is pivoted on the carrier frame C at c, and is provided with folding braces b⁵, adapted to detachably engage the said carrier frame at b⁶ whereby the sections b and b¹ are prevented from sagging when the bed is unfolded and in use. The legs b⁷ are pivoted on the section b¹, and have their upper ends connected by long links b⁸ with the links b⁹; and similar legs b⁹ are pivoted on the section b² and have their upper ends connected by long links b¹⁰ with the link b⁴; and with this arrangement the bed frame folds in the manner shown and described, and permits the mattress and bedding to be folded therewith, sufficient space being insured for this purpose. The carrier frame C is provided with projections c¹ which turn or rock on the sliding supports D, thereby providing an axis for the carrier frame to swing or move about in folding and unfolding the bed. Also as shown, these portions C¹ are adapted to slide back and forth on the supports D, the latter being provided at opposite ends with upturned portions or stops d¹ and d² to limit the said back and forth motion. These supports D are slidingly mounted on fixed guides d² which are secured to the end walls of the table body. Normally, and when the bed is folded within the table as shown in Fig. 2, these supports D occupy a position close to the fixed side wall a²; and at this time the portions c¹ are in engagement with or close to the stops d¹. Also, and at this time, the carrier frame C is supported in a horizontal position by the guides E which are disposed horizontally at opposite ends of the table; and which are secured thereto, being formed of angle iron or any other suitable material. Thus, and with this

arrangement the bed frame is held in a horizontal position, and the table is provided with a flat top, and the legs b⁷ are prevented from sagging when the bed is unfolded and in use. The legs b⁷ are pivoted on the section b¹, and have their upper ends connected by long links b⁸ with the links b⁹; and similar legs b⁹ are pivoted on the section b² and have their upper ends connected by long links b¹⁰ with the link b⁴; and with this arrangement the bed frame folds in the manner shown and described, and permits the mattress and bedding to be folded therewith, sufficient space being insured for this purpose. The carrier frame C is provided with projections c¹ which turn or rock on the sliding supports D, thereby providing an axis for the carrier frame to swing or move about in folding and unfolding the bed. Also as shown, these portions C¹ are adapted to slide back and forth on the supports D, the latter being provided at opposite ends with upturned portions or stops d¹ and d² to limit the said back and forth motion. These supports D are slidingly mounted on fixed guides d² which are secured to the end walls of the table body. Normally, and when the bed is folded within the table as shown in Fig. 2, these supports D occupy a position close to the fixed side wall a²; and at this time the portions c¹ are in engagement with or close to the stops d¹. Also, and at this time, the carrier frame C is supported in a horizontal position by the guides E which are disposed horizontally at opposite ends of the table; and which are secured thereto, being formed of angle iron or any other suitable material. Thus, and with this

arrangement, the swivel section b of the bed frame is right side up when the bed is folded within the table.

The bed is unfolded as follows:—The table is opened first, and the folded bed frame and carrier frame C are then pulled outward in the manner illustrated in Fig. 5; then the carrier frame is permitted to swing down and assume the position shown in Fig. 4, the portions c^1 at this time engaging the stops d . It will also be observed that the carrier frame is provided with catches or fastening devices F for engaging the bed frame and thereby preventing said frame from rotating relative to the carrier frame. These catches or fastening devices are then disengaged from the bed frame, allowing the latter to be rotated to a horizontal position. When this has been done, and after the braces b^5 have been adjusted in position, as shown in Fig. 3, the bed frame can then be unfolded, the legs b^7 and b^9 automatically unfolding at the same time.

When the bed frame is folded, the legs b^7 and b^9 automatically fold therewith, as shown in Figs. 2, 4 and 5, and after the members b^5 have been disengaged from the carrier frame the bed frame can then be fastened in place by means of the devices F or in any suitable manner; then the carrier frame is swung outward at the bottom, whereby the two frames are caused to assume a horizontal position. When this has been done the carrier frame and bed frame can then be shoved bodily into the table in the manner shown and described. Thus, and although the carrier frame swings outward in order to bring the bed frame into a position within the table, it is also true that the said carrier frame and bed frame are not required to swing upward and over in order to reach a position of concealment within the table. Consequently, as stated, the swivel section b is right side up when the bed is folded within the table, and the other sections of the bed frame rest thereon.

The construction shown and described, therefore, involves a novel method of combining a table with a bed in one and the same unitary structure, and is intended to solve some of the problems involved in the production of a satisfactory combination article of furniture of this particular character. For example, with this construction the table can be of the proper height, and of ordinary proportions, like an ordinary library table, being of any suitable length and of such width that it can be pushed through an ordinary doorway, and having suitable clearance underneath. In other words, the table has practically all of the essential requirement necessary for a satisfactory library table. Also, the bed when unfolded is of the proper or ordinary height and of the ordinary length, and may

be of any suitable or desired width. I do not, however, limit myself to the exact construction shown and described.

What I claim as my invention is:

1. A table bed comprising a table body, a folding bed frame in the upper portion of said table, a movable carrier frame upon which said bed frame is rotatively mounted to turn about a horizontal axis relative thereto, and a sliding connection between said carrier frame and body. 70

2. A table bed comprising a table body, a folding bed frame in the upper portion of said table, a movable carrier frame upon which said bed frame is rotatively mounted to turn about a horizontal axis relative thereto, and a sliding connection between said carrier frame and body, said connection including a pair of horizontal guides, one at each end of the table, and means engaging said guides, sliding thereon. 80

3. A table bed comprising a table body, a folding bed frame in the upper portion of said table, a movable carrier frame upon which said bed frame is rotatively mounted to turn about a horizontal axis relative thereto, and a sliding connection between said carrier frame and body, said connection including a sliding member at each end of the table, disposed in a horizontal plane, 90 and means slidable on said member, fixed in the end of said carrier frame.

4. A table bed comprising a table body, a folding bed frame in the upper portion of said table, a movable carrier frame upon which said bed frame is rotatively mounted to turn about a horizontal axis relative thereto, and a sliding connection between said carrier frame and body, means for supporting the carrier frame in horizontal position, fixed on the body forming a track on which said carrier frame slides horizontally when the bed is in folded condition, and means on said connection for permitting said carrier frame to swing about a horizontal axis, so that the carrier-frame may assume an upright position adjacent the front legs of the table. 100

5. A table bed comprising a table body, a folding bed frame in the upper portion of said table, a movable carrier frame upon which said bed frame is rotatively mounted to turn about a horizontal axis relative thereto, and a sliding connection between said carrier frame and body, said connection having means associated therewith for permitting said carrier frame to swing about a horizontal axis so, that the carrier-frame may assume an upright position adjacent the front legs of the table. 115

6. A table bed comprising a table body, a folding bed frame in the upper portion of said table, a movable carrier frame upon which said bed frame is rotatively mounted to turn about a horizontal axis relative 120

thereto, and a sliding connection between said carrier frame and body, guides fixed on said body, and means fixed on said carrier frame to rest and slide on said guides.

5 7. A table bed comprising a table body, a folding bed frame in the upper portion of said table, a carrier frame upon which said bed frame is rotatively mounted, and a sliding connection between said carrier frame

10 and body, said bed frame including pivotally connected sections, one of which sections is swiveled on the carrier frame, and said swiveled section being right side up when the bed is folded inside the table.

15 8. A table bed comprising a table body, a folding bed frame in the upper portion of said table, a carrier frame upon which said bed frame is rotatively mounted, and a sliding connection between said carrier frame and body, braces for said bed frame,

20 detachably engaging said carrier frame, and folding legs for the bed frame.

9. A table bed comprising a table body, a folding bed frame in the upper portion of said table, a carrier frame upon which said bed frame is rotatively mounted, and a sliding connection between said carrier frame

and body, and means for locking the bed frame against rotation relative to the carrier frame, when the bed is folded.

30

10. A table bed comprising a table body, a folding frame in the upper portion of said table, a carrier frame on which said bed frame is rotatively mounted, and a sliding connection between said carrier frame and body, said carrier frame being arranged to move outward bodily and then swing downward and toward the table before the bed is unfolded.

35

11. A table bed comprising a table body, a transversely folding frame in the upper portion of said table, a carrier frame on which said bed frame is rotatively mounted, and a sliding connection between one end of said carrier frame and said body, said bed frame being provided with legs having links for the automatic control thereof.
